UNITED STATES PATENT OFFICE.

ALVIN D. SANDBERG, OF KEARNEY, NEBRASKA.

CHICKEN-BROODER.

1,033,950.

Specification of Letters Patent. Patented July 30, 1912.

Application filed July 21, 1911. Serial No. 639,730.

To all whom it may concern:

Be it known that I, ALVIN D. SANDBERG, citizen of the United States, residing at Kearney, in the county of Buffalo and State 5 of Nebraska, have invented certain new and useful Improvements in Chicken-Brooders, of which the following is a specification.

The present invention relates to certain new and useful improvements in the construction of brooders such as are employed for hovering and caring for chicks which have been artificially hatched or for some reason taken from the mother hen.

The primary object of the invention is to 15 simplify and improve the construction of brooders in general, and to provide a brooder which will enable a maximum percentage of chicks to be successively reared.

A further object of the invention is the 20 provision of a brooder which embodies novel features of construction whereby the chicks are prevented from crowding together until the weaker chicks are trampled upon or injured by the stronger chicks, and which 25 provides suitable roosts for the larger and stronger chicks.

A still further object of the invention is to provide a brooder which does not require the use of artificial heat, which is simple and 30 inexpensive in its construction, and which can be compactly folded so as to occupy a small amount of space when not in use.

With these and other objects in view, the 35 invention consists in certain novel combinations and arrangements of the parts as will more fully appear as the description proceeds, the novel features thereof being pointed out in the appended claims.

For a full understanding of the invention, 40 reference is to be had to the following description and accompanying drawing, in which:—

Figure 1 is a perspective view of a 45 brooder constructed in accordance with the invention, and Fig. 2 is a transverse sectional view through the same.

Corresponding and like parts are referred to in the following description and indicated in all the views of the drawing by 50 the same reference characters.

Specifically describing the present embodiment of the invention, the reference 55 characters A designate a pair of frames which are connected at the top thereof by means of hinges 10 and are adapted to be folded together when not in use, although

they are normally spread apart as indicated in Figs. 1 and 2 of the drawing. Each of these frames A comprises a pair of spaced and parallel end bars 2 connected by a pair 60 of roosting rods 12 and also at a point toward the swinging ends thereof by a cross bar 13. A wire 14 or similar member extends between the end bars 11 immediately below each of the roosting rods 12, and a 65 strip of fabric 15 is doubled over each of the wires 14 so as to hang therefrom. This fabric may be of any preferred material suitable for retaining the heat of the chicks nestling under the same, the lower ends of 70 the various pieces of fabric terminating slightly above the ground, as indicated more clearly in Fig. 2. The pendent portions of the fabric members are formed with vertical slits 16 and the small chicks which are 75 placed in the brooder nestle under the ends of the fabric in the same manner that they would nestle under a mother hen.

For the purpose of holding the wires 14 against sagging, rings 17 are provided 80 which extend around the wires and the roosting rods 12 and serve as hangers to support the wires. When the brooder is set up in operative position, some suitable form of locking member such as the hook 18 is provided for holding the frames A against 85 spreading apart or coming together. These hooks 18 are shown as hinged upon one of the frames A and engaging studs 19 upon the opposite frame. 90

In the operation of the brooder the small chicks will nestle under the fabric strips 15 in the usual manner, and as soon as any of the chicks become sufficiently large to roost they will hop on the rods 12 instead of 95 trampling upon and injuring the weaker and more imperfectly developed chicks. Attention may also be directed to the fact that the roosting rods 12 of each of the frames A have a stepped relation so that the 100 chicks upon the lower roosting rods will still be partially protected by the fabric 15 pendent from the wire immediately under the upper roosting rod. The chicks thus have their choice of a lower and partially 105 protected roosting rod or an upper and unprotected roosting rod. Provision is thereby made for the warmth of the weaker as well as the more perfectly developed chicks, and the stronger chicks are properly 110 cared for so that they have no tendency to trample upon and injure the weaker chicks.

Having thus described the invention, what I claim as new and desire to secure by Letters Patent, is:—

1. A brooder including a supporting frame formed with a series of roosting rods, fabric supporting members extending longitudinally of the roosting rods and arranged adjacent thereto, and fabric pendent from the various fabric supporting members, the different fabric members extending downwardly toward the bottom of the supporting frame and coöperating with each other to provide a hover, the weaker chicks being designed to nestle under the hover provided by the fabric pieces, while the stronger chicks would roost upon the roosting rods.
2. A brooder including a supporting frame formed with a series of roosting rods, fabric supporting wires arranged under the roosting rods, hangers connecting intermediate portions of the wires and the roosting rods, and fabric members pendent from the various wires, the said fabric members extending downwardly toward the bottom of the supporting frame and coöperating with each other to provide a hover for the chicks, the stronger chicks roosting upon the rods as soon as they become sufficiently well developed for that purpose.
3. In a brooder, the combination of a supporting frame including a roosting rod, a wire arranged under the roosting rod, rings extending around the wire and roosting rod to support the wire, and fabric pendent from the wire.
4. A brooder including a supporting frame formed with a series of roosting rods, a wire arranged under each of the roosting rods, rings extending around the wires and roosting rods to support the wires, and

fabric members pendent from the wires and extending to the bottom of the frame, the said fabric members coöperating with each other to provide a hover for the weaker chicks, the stronger and better developed chicks being designed to roost upon the rods.

5. In a brooder, the combination of a pair of hinged frames adapted to be folded together when not in use, each of the hinged frames being formed with a series of roosting rods, means for holding the hinged frames at an angle to each other when the device is in use, and a fabric member arranged under each of the roosting rods, the said fabric members extending downwardly toward the bottom of the frame and coöperating with each other to provide a hover for the weaker chicks, the stronger chicks being adapted to roost upon the rods.

6. In a brooder, the combination of a pair of hinged frames adapted to be folded together when not in use, each of the frames including a series of roosting rods, means for holding the hinged frames at an angle to each other when the device is in use, a fabric supporting wire extending under each of the roosting rods, and a fabric member pendent from each of the fabric supporting wires, the said fabric members extending to the bottom of the frame and coöperating with each other to provide a hover for the weaker chicks, the stronger and better developed chicks being adapted to roost upon the rods.

In testimony whereof I affix my signature in presence of two witnesses.

ALVIN D. SANDBERG.
